UNITED STATES PATENT OFFICE

2,102,334

PROCESS FOR DEWAXING HYDROCARBON OILS

Earl Petty, Hempstead, N. Y., assignor, by mesne assignments, to Sun Oil Company, Philadelphia, Pa., a corporation of New Jersey

Application April 14, 1933, Serial No. 666,099

6 Claims. (Cl. 196—19)

My invention relates to a process for dewaxing hydrocarbon oils and more particularly to a process of dewaxing in which pressable wax crystals are produced by chilling wax-bearing-distillates from crude oil.

This application is a continuation in part of my co-pending application entitled "Process of dewaxing oil", Serial No. 624,968, filed July 27, 1932.

Heretofore, to produce pressable wax distillates from crude oil it required a high degree of fractionation and a very careful selection of the pressing fraction. This pressing fraction usually had a boiling range of from 450° F. to 675° F. @ 10 m/m Hg. absolute pressure.

One object of my invention is to provide a method of dewaxing hydrocarbon oils in which the fractions which can be dewaxed by pressing are extended to include oils of a boiling range up to 725° F. to 750° F. @ 10 m/m Hg. absolute pressure.

Another object of my invention is to provide a method of chilling hydrocarbon oils which will greatly improve the formation of pressable wax therein.

Another object is to produce a more oil-free wax crystal by improving the conditions under which crystallization is conducted.

Other and further objects of my invention will appear from the following description.

The accompanying figure, which is to be read in conjunction with the instant specification and which forms part thereof, shows a diagrammatic view of an apparatus capable of carrying out my invention.

In general, my invention consists of blending, under pressure, a predetermined amount of hydrocarbon such as propane with the wax bearing oil. It is to be understood that throughout this specification by "propane" is meant any of the low boiling hydrocarbons which may exist in a liquid state in the normal temperature range by the imposition of super-atmospheric pressure. Commercial propane, for example, is liquid within the normal temperature range at pressures between 80 and 120 pounds per square inch and contains at least 60% of pure C₃H₈. At atmospheric pressure it boils at approximately -45° F. and solidifies at about -300° F. These later characteristics indicate another contributory and complimentary characteristic of this diluent, viz a low viscosity. The viscosity of gasoline or naphtha normally used as a diluent in connection with dewaxing at temperature of 5° C. is an average of .00690 C. G. S. unit, whereas propane

has a viscosity at the same temperature of .00125 C. G. S. unit. This low viscosity indicates high freedom of movement and velocity of the molecular structure and has definitely proven to be very advantageous to crystallization, when it is present as a diluent. The other characteristic of low temperature of boiling makes it possible to remove the propane as the crystallization progresses. The removal of this diluent has the effect of accelerating crystallization by concentrating the amount of oil in the mother solution. In other words, the crystal is formed and cultured during the first part of the cooling by the dilution and low viscosity effect of the propane. Then the increased concentration of the oil and incidental refrigeration effect produced by allowing the propane to evaporate produces the final wax crystal. These above complementary and contributory physical effects are accomplished by the following chilling procedure. The blend is made at approximately 80 to 100° F. The chilling is divided into two stages, viz, 1st, indirect heat exchange to approximately 30° F., and 2nd, by evaporation of the propane and the incidental reduction of temperature to as low as -30° F. In the first stage the blended mixture is passed under pressure through precoolers in order to chill the same by indirect heat exchange. The precooled mixture is then passed into the evaporator-crystallizer for concentration by the removal and evaporation of the propane and incidental refrigeration or cooling. This is accomplished by reducing the pressure on the evaporator and results in the evaporation and removal of substantially all the propane. The effect of the propane upon the wax during the pre-cooling is as a diluent to reduce the viscosity of the solution and accelerate the crystallization. The final chilling, incidental to evaporating the propane, is such that a desirable wax crystal is developed due to increased concentration of the oil in the solution, producing a wax of improved filtering quality. (See co-pending patent application 632-278, Sept. 9, 1932.) This effect enables me, by the practice of my process, to extend the range of pressable wax bearing oils, or to increase the rate of filtration, and reduce the oil content of the wax. The propane from the evaporator is recovered for re-use. The chilled oil containing the wax crystals and substantially free of propane is then passed to a CO₂ stripper tower where CO₂ vapors are expanded into tower counterflow to the chilled wax distillate before it is passed to filter press. In the tower, by the stripping step, the final traces of propane are

removed and replaced with CO₂ vapors. The oil which is recovered from the pressing operation, at a very low temperature, is passed in heat exchange with the incoming mixture as the cooling medium although it is understood that any other suitable refrigerant may be employed for the indirect heat exchange step. The oil is then passed to a pressure evaporator to insure the complete removal of propane and CO₂ therefrom, 10 finally stripped by steam to remove the last trace of any of the volatile products, and then passed to storage and further processing.

If desired, the process could be modified by combining the steps performed in the stripping tower and evaporator by passing CO₂ vapors directly into the oil transfer line from the exchanger to the evaporator, or direct into the evaporator, thereby eliminating the stripping tower. Handling of vapors would be combined.

20 This is done as shown in the drawing by means of line 38, which is controlled by valves 37 and 42. When valves 37 and 42 are open, CO₂ will pass directly into line 12 into the evaporator crystallizer and serve to strip the propane from the oil.

25 More particularly, referring now to the drawing, the distillate to be dewaxed is pumped from storage tank 1 by pump 2 through valved line 3 into blending tank 4. Propane, under pressure and in the liquid state, is pumped from tank 5 through line 6 by pump 7 into line 8 which enters the blending tank 4, in which a thorough mixture of the oil to be dewaxed with the propane, is effected. It is to be understood that suitable agitating means may be provided in the blending 35 tank. The mixture or solution is pumped through valved line 9 by pump 10, through heat exchangers 11. These heat exchangers may be of any suitable type. The drawing illustrates a diagrammatic view of scraped surface heat exchangers. The solution is chilled in heat exchangers 11 and passes through line 12 into the evaporator crystallizer 13, in which the pressure is reduced to allow the propane to evaporate to 40 secure additional and further chilling. If desired, propane may be passed through line 14 and pumped by pump 15 through line 16 into the evaporator crystallizer to secure additional and further cooling.

45 The gaseous propane leaves the evaporator crystallizer 13 through line 17 and pressure reducing valve 117 and may be recovered by any suitable means. Separator 18 is provided to insure that no oil is carried out of the system, the oil returning through line 19. Pump 15 is adapted to take suction through valve line 20 for recirculation of the solution. Chilled oil containing pressable wax crystals is withdrawn from evaporator crystallizer 13 through valved line 21 by pump 55, valve 122 being closed, and passes 50 through line 121 into CO₂ stripper 50. CO₂ vapors from cylinders 51 or 52 are passed into this stripper through pipe 151 and pipe 152 controlled by valves 153 and 154 and due to the partial pressure effect, the remainder of the propane 55 is removed. The propane and CO₂ vapors are taken off through vapor line 53 and pump 54 to be compressed and recovered. The chilled stripped liquid is withdrawn from the tower 50 through line 21a by means of pump 55a by which it is fed to the filter or pressing system. (It is not intended to use the CO₂ as a refrigerant at this stage. The tower would be carefully insulated and the amount of CO₂ vapors used would not remove any heat, and the effect of these vapors 70 would be to remove the entrained propane and

thereby give slight refrigeration effect from evaporation of propane, due to partial vapor pressure effect.) Filter presses 22, 23 and 24, as shown, are arranged in parallel.

5 The wax leaves the filter presses through lines 28, 29 and 30 and passes into wax receiver 31 which is provided with a fitting 32 through which a reduced pressure may be placed on the wax receiver to evaporate therefrom all traces of volatile propane and/or CO₂. The cold dewaxed oil leaves the filter presses through lines 32, 33 and 34 through line 35, and is pumped by pump 36 through the heat exchangers 11 to chill the incoming solution. The oil leaves the heat exchangers 11 through line 39 and passes into 15 steam stripper 46. The dewaxed oil, freed of the solvent, is then pumped by pump 48 into storage tank 49. Recycle with the undewaxed oil may be practiced to reduce cold test and thickness of material being dewaxed by diverting a 20 portion of the dewaxed oil in line 39 through line 44 by means of pump 45 or through line 44a (or the wax distillate may be diluted, as conventionally practiced, with gas oil or kerosene).

25 The filter presses may be of the conventional type or may be special continuous or batch type filters.

It will be seen that I have accomplished the objects of my invention. I am enabled to produce pressable wax from distillates of a greater 30 boiling range. By my method of chilling, I am enabled to produce pressable wax where it has been impossible heretofore to do so, and also to produce a greater amount of pressable wax for a given fraction, enabling the complete dewaxing 35 thereof. An increased crystal formation is achieved by the use of propane as a diluent accompanied by the manner in which I chill the solution. I preclude the danger of fire in the press room by keeping it in an atmosphere of 40 inert gas.

45 It will be understood that certain features, sub-combinations and operations are of utility and may be employed without reference to any other features and sub-combinations. This is contemplated by and is within the scope of my claims. It is further obvious that various changes may be made in details within the scope of my claims without departing from the spirit of my invention. It is, therefore, to be understood that my invention is not to be limited to the specific details shown and described.

50 It will be understood, further, that, while I have given CO₂ as an example of one gas for stripping, any normally gaseous material relatively inert and of a proper boiling range may be used as the stripping agent. A non-inflammable gas is preferred. Nitrogen may be used. Gas of combustion containing largely nitrogen and CO₂ is suitable.

55 Having thus described my invention, what I claim is:

1. In a dewaxing method for hydrocarbon oils in which liquefied normally gaseous hydrocarbons are admixed with an oil to be dewaxed, the liquefied hydrocarbons expanded to chill the oil and the wax then removed from the oil, the step of stripping the chilled oil of residual normally gaseous hydrocarbons after the expansion step by means of an inert gas lower boiling than the 70 normally gaseous hydrocarbons.

65 2. A method of dewaxing hydrocarbon oils including the steps of mixing the oil to be dewaxed with liquefied normally gaseous hydrocarbons, chilling the oil by evaporating normally gaseous 75

- hydrocarbons mixed therewith, removing the residual hydrocarbons from the chilled oil by stripping with carbon dioxide in a stripping zone, and then dewaxing the oil.
- 5 3. A method of dewaxing hydrocarbon oils including the steps of mixing the oil to be dewaxed with liquefied propane, cooling the mixture by indirect heat exchange, chilling the cooled oil by evaporating the propane, removing the residual hydrocarbons from the chilled oil in a stripping zone by stripping the oil with a gas lower boiling than the propane and then dewaxing the oil.
- 10 4. A process of dewaxing hydrocarbon oils including the steps of adding a low viscosity normally gaseous hydrocarbon diluent to the oil to facilitate crystallization of wax in the oil during a pre-cooling stage, chilling the diluted oil by indirect heat exchange in a first chilling zone to initiate crystal formation, evaporating substantially all of the low viscosity diluent from the chilled oil in a second zone of chilling to concentrate the amount of oil in the mother solution and secure final wax crystal development, then removing the residual diluent from the chilled oil by stripping with an inert gas lower boiling than the diluent and mechanically removing the wax from the oil.
- 15 5. A method of dewaxing a hydrocarbon dis-

tillate of boiling range from 450° F. to 750° F. @ 10 m/m Hg. absolute pressure including diluting the oil with low viscosity normally gaseous hydrocarbons under pressure and in the liquid phase and in sufficient quantity to serve as an accelerator of crystallization by low viscosity effects during a pre-cooling stage, cooling the diluted oil by indirect heat exchange to approximately 30° F., removing substantially all the diluent from the oil by evaporation which by incidental physical effects results in cooling and co-incidental concentration of the oil in the mother solution and produces a further developed wax crystal substantially oil free, carried in oil, then freeing the oil of residual diluent by stripping with a normally gaseous, non-inflammable material of a lower boiling range than the diluent, and mechanically removing the wax crystals from the oil.

20 6. A method of dewaxing hydrocarbon oils including the steps of mixing oil to be dewaxed with a liquefied, normally gaseous hydrocarbon diluent, then chilling the mixture and increasing the concentration of the oil in the mixture by stripping the diluent hydrocarbon from the oil with a normally gaseous, non-inflammable material of a lower boiling range than the diluent and removing the wax from the oil.

EARL PETTY.
